UNITED STATES PATENT OFFICE.

HOWARD F. SNYDER, OF NEWTON, IOWA, ASSIGNOR, BY MESNE ASSIGNMENTS, TO THE MAYTAG COMPANY, OF NEWTON, IOWA, A CORPORATION OF DELAWARE.

WRINGER.

Application filed November 11, 1920. Serial No. 423,225.

This invention relates to wringers, such as are ordinarily used in connection with power washing machines. Among the objects of my invention are: to make the wringer separable from the reversing gear casing; to make both wringer rolls readily removable from the wringer frame; to construct the driving shaft of the driving roll in sections so that the roll may be readily separated from the driving gear; to improve upon the direction reversing mechanism; to provide means for automatically shifting the inclination of the drain plate upon reversing the direction of rotation of the wringer rolls; to releasably secure the top wringer roll in the pivoted top section of the frame; to provide an improved shaft bearing; to provide improved water drainage mechanism for a wringer; to provide improved locking mechanism for the pivoted top of a wringer; and such further objects, advantages and capabilities as will later more fully appear.

My invention further resides in the combination, construction and arrangement of parts illustrated in the accompanying drawings, and while I have shown therein a preferred embodiment I desire the same to be understood as illustrative only and not as limiting my invention.

30 In the accompanying drawings:

Fig. 1 is an elevation of a wringer embodying my improvements.

Fig. 2 is an inner face view of the gear casing head, showing the same with wringer detached.

Fig. 3 is an end view of the wringer, showing that face which is adapted to be connected to the face shown in Fig. 2.

Fig. 4 is a broken plan view, on a larger scale than Fig. 1, of my improved wringer, showing the top portion released and turned over to expose the parts beneath.

Fig. 5 is an outside end view of the wringer.

Fig. 6 is a substantially central, vertical section of the structure shown in Fig. 1.

Fig. 7 is a broken, vertical, longitudinal, substantially central section through the structure shown in Fig. 1.

50 My new wringer comprises the separably connected gear head H and wringer W. The head H comprises the gear casing 1 in which the driving gear and wringer reversing mechanism are located and the supporting sleeve 2 by means of which the whole structure is supported upon a shaft connected with a

washing machine. Slidably mounted in the head as shown more clearly in Figs. 1 and 7 is the locking bolt 3 operated by means of the handle 4 and crank 5, which locking bolt is adapted to engage perforations in the flange 60 of a member suitably connected to the washing machine.

Rotatably mounted in the head H is a shaft 6, an end of which is suitably notched to engage the upper end of a driving shaft appropriately connected to the driving mechanism. Near its central part, this shaft is provided with a non-cylindrical part 7, shown in this drawing as being squared. On this squared portion slides a sleeve 8, having projections 9, 70 or the equivalent thereof, upon its ends. Centrally, this sleeve is provided with a reduced portion which forms a groove 10 in which is located a block 11, shaped to fit closely against the curved face of the sleeve, and provided in one face with a slot in which operates a pin 12 on a disk 13 connected with the reversing handle 14. Loosely mounted on shaft 6 is a pair of gears 15 and 16, which are adapted to alternatively transmit motion to the gear 17, 80 mounted on the inner end of shaft 18 and secured thereto. The faces of gears 15 and 16, facing sleeve 8, are provided with notches or projections, to engage the corresponding parts 9 of the sleeve. It will therefore be 85 seen that when the crank 14 is turned from the neutral position shown in Fig. 7 sleeve 8 will be forced either upwardly or downwardly into engagement with one or the other of gears 15 and 16, and therefore that, when shaft 6 is driven, gear 17 and shaft 18 will be caused to rotate in one or the other direction.

The inner end of shaft 18 is formed with an aperture 19, which is non-cylindrical in 95 form, and a flange which has its edge notched to form teeth 20, thereby providing a driving gear for co-operation with the gear 21 on end of shaft 22 of the upper wringer roll. It is obvious that a separate gear might be 100 mounted upon and secured to the inner end of shaft 18. The non-cylindrical end of shaft 23 is shaped to fit opening 19, but to leave a sufficient amount of play between the parts so that the opposite end of the shaft can be 105 raised to remove the roll from the frame.

The head H is provided with a pair of apertures 24 and the wringer with a pair of apertures 25 adapted to register with each other, so that the head and wringer can be 110

detachably secured by means of bolts 26. In the event of breakage of the frame or, if for any other reason it is desired to separate the head and wringer this may be accomplished by removing the bolts 26. It is obvious from the above that if either the head H or the wringer frame should be broken, they may be separated and a new one supplied for the broken one, thereby reducing the amount of loss resulting from such breakage. This supply of parts is also facilitated by the ease with which the wringer rolls may be removed and replaced, either in the event of wearing out of the rolls or the breaking of one or the other of them or of the frame.

The upright end members of the wringer are connected by a transverse connecting member 27, comprising a ridge 28, or the equivalent thereof, and a pair of lateral members sloping downwardly away from the ridge. Supported loosely and removably on the ridge 28, is a drain plate or board 29 which is rockable to throw the water to one side or the other of the wringer. This drain plate 29 has a pair of end extensions 30 and 31 reaching out into relatively narrow ways formed by the spaced apart upright members of the frame and tending to hold the drain plate loosely in proper position. The opposite sides or vertical walls of these narrow ways are provided with recessed ways 31' for receiving angularly shaped roller casing members hereinafter described. As shown clearly in Figures 5 and 7, one end of the frame is provided with an extension 32 substantially cradle shaped. The end of extension 31 has an upwardly extending toothed projection 32. This projection 32 has a depending toe or lug 32' adapted rockably and loosely to be in the cradle of the extension 32'. The teeth of projection 32 may take the form of a segment of a gear as shown in Figure 5. On the end of shaft 23 is a sleeve 33 which has a projection 34 which may take the form of a segment of a gear, and which cooperates with the projection 32. On the opposite side of the sleeve 33 from projection 34 is a hollow threaded projection 35, in which is mounted a friction member 36 which may have its tension on shaft 23 varied by means of a threaded headless bolt 37. This makes it possible to have the proper amount of friction between shaft 23 and block 36 so that drain board 29 will be positively rotated a short distance in an opposite direction from shaft 23, and yet the friction does not need to be excessive at any time, as the same may be adjusted in accordance with the amount of wear which occurs. It will be seen from the above that if clothing is being fed into the wringer from the left side as shown in Fig. 6 the drain plate will occupy the position there shown. If, however, the wringer is reversed and the roll starts to move in the opposite direction, drain plate 29 will

immediately have its inclination reversed so that it will drain water to the right side as shown in Fig. 6. This action is entirely automatic so that the operator does not need to give any attention to the drain board unless block 36, which may be made of leather, wood, or the like, becomes worn to such an extent that the drain board fails to tilt. In this event, a slight turn of bolt 37 will cause a sufficient change in pressure to make the drain board react again as it should. It will also be evident that the rib 28 along the top of the wringer casting 27 upon which the water plate rocks, acts as a dam to keep the water from running back under the plate. In addition, this rib 28 also acts as a support to take the strain in case the lower roller 23 should become wrapped with fabrics and cause an undue pressure downwardly on plate 29. Thus it will be seen that this rib 28 has a threefold purpose, firstly, it acts as a pivot for the drain plate 29, secondly, as a dam to keep water from running back under the plate, and, thirdly, as a support for the plate. It will also be evident that the high sides and ends as shown in plan view in Figure 4 about the drain plate trunnion are provided to keep the water from running out at these points. One of the main advantages of this construction resides in having the plate 29 loosely and detachably mounted in this position so that when the wringer is released the lower roller may be lifted out and then the drain plate 29 may be lifted out.

Pivoted to the upright end members of the frame is a pair of cross members 38 and 39, to which is pivoted a cap plate 40, having a pivotal member or members 41, flattened as shown in Fig. 4 and as indicated by dotted line 42 in Fig. 5. It will be seen that when the cap plate 40 is in the position shown in Fig. 5 the member or members 41 will engage the hooks at the upper ends of members 43 to hold the cross bars 38 and 39 down in the position intended for wringing, but that when cap plate 40 is turned to the position shown in Fig. 4 the pivots will be released from the hooks so that the cap plate, cross bars, and upper ringer roll may be turned on the pivots connecting the cross bars with the end members of the frame. This structure makes it very easy to release the tension on the rolls, in the event the hand should get caught between them or clothes get bunched in going through the wringer. It also makes it easy to open up the wringer for the purpose of taking out the wringer rolls and drain plate.

Each wringer roll shaft is provided adjacent each end with an anti-friction device, the structure of which is shown most clearly in Fig. 7. This comprises a sleeve 44 which closely fits the shaft but is easily rotatable thereon, and has one end reduced in diameter

- to form a shoulder, approximately centrally of the length of the sleeve. Another sleeve 45 is fitted snugly to the exterior surface of the reduced portion of sleeve 44 and is so proportioned as to leave a groove at its inner end for the reception of roller members such as balls or cylinders 46. Around these roller members is arranged a roller casing 47, which as shown in Fig. 5, is preferably angular and 5 adapted to fit in the recessed ways 31' formed in the opposite sides of the open mounted spaced apart upright end members whereby to prevent the rotation of the casings in the end members of the frame while at the same 10 time permitting the free removal of the bearing casing by lifting them out vertically. Projecting from one face of each of cross bars 38 and 39 is a pair of lugs 48, having perforations in their ends for the reception of cotter 15 pins 49 or the like, by means of which the bearings for the upper wringer roll are held in position in the cross bars, so that the upper roll will be retained assembled with the upper or swinging element of the frame. It will 20 be seen that if it is desired to remove the upper roll this is easily accomplished by opening the wringer as shown in Fig. 4 and removing the cotter pins 49 whereupon the roll can be lifted out. If desired, an end of one 25 of the shafts 22 and 23 may be extended sufficiently to receive a wringer handle, if for any reason it is desired to make use of same. When a handle is not attached to this end the same will be covered by a finishing and 30 protecting cap 50 as shown in Fig. 7.

It is of course understood that the specific description of structure set forth above may be departed from without departing from the spirit of my invention as set forth in this 35 specification and the appended claims.

Having now described my invention, I claim:

1. In a wringer, a gear casing having a bearing in one wall thereof, a shaft operable in said bearing, a gear on one end of said shaft within the casing and adapted to mesh with a driving gear, a gear at the other end of said shaft and adapted to drive a wringer roll, a wringer roll having a shaft, and a readily separable connection between said shafts.
  2. In a wringer, a gear casing having a bearing in one wall thereof, a shaft operable in said bearing, a gear on one end of said shaft within the casing, a gear on said shaft outside of the casing, a third gear meshing with said second gear, a wringer roll shaft carrying said third gear, a second wringer roll shaft in alinement with the first named shaft, and a readily separable connection between said second wringer roll shaft and said first mentioned shaft.
  3. In a wringer, a wringer roll having a shaft, a shiftable drain board below said roll, drain board actuating means frictionally engaging said wringer roll shaft, means for adjusting the frictional contact pressure, and connections between said drain board actuating means and said drain board so that the latter will be caused to shift upon reversal of direction of rotation of the wringer roll so as to draw the escaping water in the desired direction.
4. In a wringer, a frame, a pair of rolls in said frame, a drain board on said frame below said rolls, and mechanism for automatically reversing the inclination of said drain board upon reversal of the direction of rotation of the rolls, said mechanism including a sleeve loosely mounted upon a wringer roll shaft, a friction member carried by said sleeve and frictionally held against said shaft but capable of slipping with relation thereto, and interengaging projections on the drain board and sleeve adapted to cause the one to move upon movement of the other.
5. In a wringer, a support, a drive shaft on the support and forming a portion of a quick detachable connection, a wringer frame on the support, a wringer roll shaft freely mounted on said frame for detachment and having one end formed with a cooperative portion of the quick detachable connection with said drive shaft, a drain board loosely and detachably supported on said frame beneath said roll shaft, said drain board and roll shaft having freely disengageable driving portions adapted to cause the tipping of said drain board upon the rotation of said roll shaft.
6. In a wringer, a frame, a roll rotatably mounted therein, said roll having a shaft, a sleeve on said shaft provided with a friction producing means, means for regulating the amount of friction between the shaft and friction producing means, a rockable drain board in the frame having a projection, a projection on the sleeve adapted to co-operate with the first named projection to cause rocking of the drain board upon rotation of the shaft.
7. In a wringer, a frame, a wringer roll shaft having bearings in said frame, a drain board rockably mounted in said frame, a projection on one end of said drain board, and means loosely mounted on an end of said shaft and having means mounted therein frictionally engaging said shaft, the first mentioned means engaging said projection to cause rocking of said drain board upon rotation of the rolls.
8. In a wringer, a frame, a rockably and detachably mounted drain plate therein, a driving shaft, a lower wringer roll having a shaft detachably connected to the driving shaft, said frame having an upper pivoted section, and an upper roll detachably secured in said pivoted section, the drain plate and

wringer rolls being so arranged in said frame that upon release of said pivoted section they can all be readily lifted from the frame.

9. In a wringer, a frame having a drain plate rockably mounted thereon, wringer rolls on said frame, a toothed driving member having a frictional mounting on one of said roll shafts, said drain plate having a toothed portion meshing with the teeth of said driving member whereby to rock said drain plate on rotation of said wringer roll shaft.

10. In a wringer, a frame having spaced end bearings, one of which is formed with a substantially cradle shaped extension, a drain board having end members rockably disposed in said bearings, one of the members being formed with an extension having a depending lug lying in the cradle and an upstanding toothed portion, a lower roll shaft mounted in the bearings above the drain board, means on the roll shaft having frictional engagement therewith, said means having toothed engagement with the upstanding toothed portion of the extension for rocking the drain board on rotation of said roll shaft.

11. In a wringer, the combination with a wringer frame, a pair of wringer rolls operatively connected to rotate in opposite directions, a deflector tiltably supported below said rolls for draining water in a direction from which clothes are being wrung, a device rotatably supported on the shaft of one of

said rolls, adjustable frictional means for drying said device from said shaft, and means controlled by said device for automatically shifting said deflector to different positions according to the direction of rotation of said shaft. 35

12. In combination with a washing machine head having therein a power driven horizontal shaft projecting from the head and terminating in a gear formed with an angularly shaped bore, a wringer frame detachably connected to the head so as to receive the bored gear within the wringer frame, said wringer frame having open top bearings, a wringer roll shaft having end bearings lying loosely in the open bearings of the wringer frame, one end of the wringer roll shaft being slightly smaller than the angular bore of the gear and being angular in shape and adapted rather loosely to fit within the angular bore of the gear whereby the wringer roll may be driven from the shaft and may be quickly removed from the wringer frame by lifting the opposite end of the wringer roll shaft or whereby the wringer frame may be detached from the head, and a second wringer roll having a gear meshing with the first mentioned gear. 40 45 50 55 60

In witness whereof, I hereunto subscribe my name to this specification.

HOWARD F. SNYDER.
